SPOTLIGHT FOR MOVIE CAMERAS

Robert B. MacLeod, Jr., Marblehead, and Hendrik A. J.
de Vos, Wenham, Mass., assignors to Sylvania Electric
Products Inc., a corporation of Delaware

Filed Mar. 11, 1968, Ser. No. 10,916

Term of patent 14 years

(Cl. D48—20)

FIG. 1

FIG. 2

FIG.3

FIG.4

FIG.5

FIG.6

FIGURE 1 is a perspective view of a spotlight for movie cameras embodying our new design.

FIGURE 2 is a side elevational view thereof.

FIGURE 3 is a front elevational view thereof.

FIGURE 4 is a rear elevational view thereof.

FIGURE 5 is a top plan view thereof.

FIGURE 6 is a bottom plan view thereof.

The dominant features of our design reside in the portion shown in full lines.

We claim:

The ornamental design for a spotlight for movie cameras, as shown and described.
